UNITED STATES PATENT OFFICE.

FRANK WILCOMB, OF NORRISTOWN, PENNSYLVANIA, ASSIGNOR TO WILDMAN MFG. CO., OF NORRISTOWN, PENNSYLVANIA, A CORPORATION OF PENNSYLVANIA.

KNITTING-MACHINE.

1,244,267.

Specification of Letters Patent. Patented Oct. 23, 1917.

Application filed July 5, 1916. Serial No. 107,817.

To all whom it may concern:

Be it known that I, FRANK WILCOMB, a citizen of the United States, and resident of Norristown, Pennsylvania, have invented 5 certain new and useful Improvements in Knitting-Machines, of which the following is a specification.

The invention consists in the features and combination and arrangement of parts hereinafter described and particularly pointed out in the claims.

In the accompanying drawings—

Figure 1 is a vertical sectional view of a machine embodying features of my invention.

Fig. 2 is a side view of the machine or knitting head of Fig. 1.

Fig. 3 is a plan view of the cap of the machine and associated devices.

Fig. 4 is a plan view of a removable sectional gib or ring to permit the removal of needles.

Fig. 5 is a developed view of the web holder cam.

Fig. 6 is a detail sectional view of the means employed in pressing the needle beards.

Fig. 7 is a similar view of the web holder cage.

Fig. 8 is a view of a web ring.

Fig. 9 shows a modification.

The needle cylinder 1 may be of different forms but, for illustrating my invention I disclose one of tapered shape having the usual guide grooves. The needles are driven by jacks 2 but they may be driven by direct engagement with needle cams. These cams are indicated generally at 3.

At the top of the needle cylinder is supported a web ring 4 having grooves forming continuations of those in the cylinder 1 for guiding the needles and having slots 5 for guiding the web holders 6.

The mechanism for pressing the needle beards may assume different forms and still embody my invention therein, but in the particular construction illustrated this presser organization includes a presser wheel, or other member, 7 arranged inside 50 of the needle circle or row and means outside said row, against which the beards are pressed when the needles are forced or de-

flected outwardly by the inner presser member or wheel bearing on their backs. The means outside the needle row consists of a 55 ring or cylinder like body 8 which is supported upon a shoulder 9 of the needle guiding walls of the needle cylinder 1 and to which walls it is clamped by screws 10 seated in a cage 11, hereinafter referred to, the 60 said screws bearing on soft metal plugs or pins 12 mounted in the presser ring. The purpose of these soft metal plugs is to prevent damage to the needle guiding walls to which the presser ring is clamped. 65

The interior surface 12' of this presser ring, which is the presser surface, is at an inclination to the plane or line of the needle movement and though the interior opening of the ring may be flared downwardly its 70 surface converges downwardly with respect to the needle plane, so that as the needle recedes it moves into a progressively contracting space. The invention, as above stated, is not limited to a tapered needle 75 cylinder, nor is it limited to the particular shape shown of the interior of the presser ring.

One object of this improved beard pressing means is to maintain such control of the 80 beards after pressing takes place and the old loop is on the beard, as will prevent the straining or bursting of these old loops which ordinarily is due to the release of the beard after it passes into the old loop. In 85 carrying out this part of my invention I maintain the beard in pressed or partly pressed condition after the usual pressing function has been performed but at the same time I avoid crimping the nose of 90 the needle which would result in rendering the same unfit for use.

By reason of the pressing surface 12' of the outside presser ring being inclined to the plane of the needle movement, the beard 95 will be pressed as it enters the pressing zone of the ring and a continuing pressure will be applied to the lower end of the beard as the needle moves to its low point, but because of the upward flare of the space 100 in which the needle is moving downwardly the nose of the needle will not be crimped and the needle, therefore, will not be damaged.

The inclined presser surface will hold the beard under pressure or control from the time the beard passes through the old loop until the needle has reached the lower limit 5 of its retracting movement, and thus bursting of the old loops will be avoided. Heretofore it has been the practice to relieve the beard immediately after the beard point has passed through the old loop, and as several 10 adjoining needles are disposed at one time with their beards through the old loops, these loops were, by the release of the beards, subjected to considerable strain from these released beards acting individually and collectively and tending to burst them.

The pressing of the beard to pass it through the old loop is effected, as above intimated, by the inner presser member 7 forcing the needle outward against the out- 20 side presser ring, holding it in this position until the beard passes entirely through the old loop, after which the inside presser wheel, having passed the needle, released it, and thus the needle is permitted to resume 25 its normal working plane, but the needle beard still remains in contact with the presser surface 12' of the outside presser ring and is thereby prevented from opening, or at least to such an extent as would cause 30 bursting of the loop, and this continued pressing of the needle beard also has the effect of passing the needle through the loop with the least possible resistance.

It will be seen from the above that the 35 pressing of the beard and maintaining it pressed or partly pressed throughout its retraction and until after it casts its loop and the avoidance of damage to the needle nose by crimping it are effects due to the co- 40 operation of the inner presser device and the outer presser ring having an extended pressing surface arranged at an inclination to the normal working plane of the needle and converging downwardly in respect 45 thereto, there being sufficient space at the nose of the needle when retracted and when the needle is released from the inner presser element to avoid crimping of the head, but the downwardly converging planes of the 50 surface 12' and the guiding surface of the cylinder being in such relation as to maintain the beard pressed or partly pressed during its retracting movement. When the 55 needle rises it, of course, moves in its normal plane, and the beard will open gradually as it moves along the surface 12' which diverges upwardly in respect to the plane of movement of the needle. The outer 60 presser ring may be formed in sections, or elements having beard pressing surfaces may be arranged in a circle about the needle row.

The inner presser wheel of member 7 is mounted on a pin 18 of a support 14 depending from an arch shaped arm 15 pivoted at 16 to a bracket 17 adjustably held

by a screw 18 passing through a slot 19 of the bracket into the cap 20 which incloses the knitting elements, as will be made clear hereinafter. This cap is held in place by latches 20^a pivoted on pins 20^a beneath the 70 ring 57 and locked in place by springs 20^b which have projections entering openings in the latches. The springs also serve to hold the latches on their pivots. The arm 15 at its free end is locked in position by 75 a latch 21 pivoted on the screw 22 passing through the bracket 23 into the cap or cover 20. The free end of the arm 15 fits in a notch 24 of the bracket 23, Figs. 1 and 3, and the latch works transversely through a 80 notch or slot 25 in the bracket and a notch 26 in the end of the arm.

The latch is notched at 27 and when turned by pressure on the finger piece or projection 28, Fig. 3, this notch 27 is brought 85 into line with the free end of the arm 15 and said arm may then be lifted, withdrawing the presser wheel 7 from within the needle row and withdrawing also the yarn feed finger 29 which, as shown in Fig. 1, is 90 carried by the said arm 15.

When the arm is down in position it is locked by turning the latch into the position shown in Fig. 3, this turning movement being effected by pressure of the finger upon the projection 27.

The arm 15 may be adjusted to set the presser wheel in the desired position radially in respect to the needle row by the screw and slot at 18, 19, and for this purpose also the bracket 23 is slotted back to the point 23' to permit the free end of the arm 15 to partake of movement during this adjustment.

Adjustment of the presser wheel circumferentially of the needle row to set it accurately in position for pressing the needles is effected by turning the cap or cover 20 which supports the presser carrying arm 15.

This adjustment is effected by means of 110 a block 28' rotatable on the upper reduced end of the post or standard 29 which, with a like post 29', aids in supporting or sustaining the upper structure containing the knitting elements in proper position, these 115 posts extending up from the base ring 30 as shown in Figs. 1 and 2. The turnable block 28' is grooved or slotted diametrically at 31 and a pin 32 secured to and depending from the flange of the cap or cover enters 120 this slot, so that by turning the block about the post 29 the pin 32 will be moved and the cap adjusted circumferentially. When the proper adjustment has been made the block can be fixed in position by a set screw 125 33. It will be understood that only slight adjustment of the inside presser member is necessary.

The system of pressing above described 130 permits removal of the inner presser element

so that the machine can be turned around and the needles can be operated without casting off their stitches.

Web holders.

- 5 The machine shown is of such small diameter that it has been found impracticable to employ sliding web holders because their inner ends would nearly or quite meet at the center of the cylinder, which, for illustration, may be only one-half inch in diameter, and no room would be left for the fabric. The web holders 6, therefore, are pivotally mounted at 34 in a plane considerably lower than their nose ends and at points a considerable distance out beyond the circle in which the nose ends lie, so that these nose ends will move in the arc of a circle, the chord of which is sharply inclined downwardly and inwardly, and as shown the nose end and the lower projection of the web holder which ordinarily would constitute the fabric supporting member need not have any movement beyond the inner surface of the web ring 4. 70
- 25 This web holder performs the functions of supporting the newly fed yarn, while the needle is taking it, thus providing a divisional space between the new yarn and the old loop for pressing; preventing the fabric from rising when the needle advances to take the yarn, and feeding the new yarn in position against the needle stem to be taken by the needle beards. 80
- 35 For performing the first mentioned function *i. e.* of supporting the new yarn separated from the fabric loops, the yarn is simply laid on the tops of the web holders and for feeding the yarn against the stems of the needles, preventing it from ballooning and insuring that the beards will seize it, the web holders are provided with abrupt shoulders 37, the vertical faces of which perform the functions just mentioned. 90
- 45 Reverting to the web holder supporting means, the presser ring or unit 8 is provided with a radially slotted enlargement or portion 42 grooved circumferentially at 43 to receive the trunnions 34 on the web holders. 100
- 50 The slotted formation guides the web holders and sustains them laterally. The web holders are simply dropped into place and the whole series is held in proper working position by a guard plate or ring 45 which rests on their upper curved tops. 110
- 55 This ring fits within the upper ring 46 of the web holder cage 11 and is held thereby against lateral displacement. It is held down in place by the cap 20. 120
- 60 Any web holder can be lifted out, by removing the cover or cap 20 and then lifting off the guard plate or ring 46, thus giving ready access to all the web holders. 125
- 65 The web holders have their tail portions guided in slots between the walls 47 of the cage 11, and the outer ends of these tails engage the cam groove or slot 48 of the web holder cam ring 49, which encircles the cage 11, and lies between said cage and the cap or cover 20 needing no other fastening 70 or support. The presser unit 8 forms also a part of the web holder bed, being slotted to receive and guide the web holders and being pinned at 50 to the web holder cage 11. The web holder cam ring has a pin 51 extending out through a notch 52 in the lower edge of the cap or cover 20 and when the cover is turned to adjust the presser wheel 7 to the proper position circumferentially of the needle row, the web holder cam ring is likewise adjusted, by the pin 51. 75
- 80 For adjusting the web holder cam section 49, Fig. 5, vertically to get the proper throw of the web holders, I provide a vertically adjustable collar 53 on the post 29', 85 which is adjusted by a nut 54 and held in any adjusted position by a set screw 55. The collar is guided and held against turning by a pin 56 extending down from the ring 57 screwed to the posts 29, 29', said pin 90 passing through the plate 58 on the collar. The collar has pins 59 fixed in its upper plate passing through slots 60 in the ring 57 into the cam section 49 of the web holder cam ring. Now by adjusting the collar vertically the said cam section will be adjusted also. The pin 51 in this adjusting movement can move up or down in the notch 52 and in all positions it will hold the web holder cam ring in proper circumferential 95 position. 100
- 95 The described presser elements can be used in straight bar machines.
- Certain features relating to the needle jack and rocking implements, such as web holders, have been made the subject of other applications, Serial Numbers 107107, 107108 and 107109, (renewal No. 175211,) filed July 1, 1916, and 136737, Dec. 13, 1916. 110
- What I claim is:
1. In a spring beard needle knitting machine, spring beard needles, a presser device acting against the backs of the needles to force them outwardly from their normal plane, and presser means on the other side of the needle row against which the beards are pressed, said latter means having a presser surface convergent in relation to the normal plane of retracting movement of the needle, said surface acting to close the beard to pass through the old loop when the needle is forced against it from its normal plane and maintaining the beard pressed or partly pressed during the remainder of the needles retraction movement and after the needle has been released by the presser device first mentioned, substantially as described. 115
  2. In a spring beard needle knitting machine, spring beard needles, a presser de- 130

vice acting against the backs of the needles to force them outwardly from their normal plane, and presser means on the other side of the needle row against which the beards are pressed, said latter means having a presser surface convergent in relation to the normal plane of retracting movement of the needle, said surface acting to close the beard to pass through the old loop when the needle is forced against it from its normal plane and maintaining the beard pressed or partly pressed after the inside presser has released the needle.

3. In a circular spring beard needle knitting machine, a circular row of spring beard needles, means within the needle row for forcing the needles outwardly from their normal plane for pressing, means encircling the needle row and having a pressing surface for each needle convergent in respect to the normal plane of movement of the needle toward its retracted position, said encircling means by contact with the beard of the deflected needle, closing the beard to pass through the old loop and thereafter holding the beard pressed or partly pressed during further retracting movement of the needle, the convergent relation of the pressing surface and the normal working plane of the needle affording sufficient space to avoid crimping the nose of the needle, substantially as described.

4. In a circular spring needle knitting machine, a circular row of spring beard needles, means within the needle circle for deflecting the needles outwardly from their normal plane for pressing, a ring like member encircling the needles and which closes the beards to pass through the old loops when the needles are deflected, said ring having an extended surface converging or tapering in the direction of the retracting movement of the needle relative to the normal working plane of the needle, said extended surface maintaining control of the needle beard to keep it pressed or partly pressed to prevent bursting the loops, substantially as described.

5. In combination in a circular knitting machine, spring beard needles, a presser device inside the needle row to deflect the needles outwardly from their normal plane, a presser ring encircling the needle row and having a surface to press the beards of the deflected needles, pivoted web holders, and bearings for the pivoted web holders carried by and arranged on the outer side of the said ring, substantially as described.

6. In combination in a circular knitting machine, spring beard needles, a presser device inside the needle row to deflect the needles outwardly from their normal plane, a presser ring encircling the needle row and having a surface to press the beards of the deflected needles, pivoted web holders, and

bearings for the pivoted web holders carried by and arranged on the outer side of the said ring, said ring being slotted to guide the web holders between the needles, and to divide the presser into separate units or surfaces one for each needle, substantially as described.

7. In combination in a circular knitting machine, spring beard needles, a presser device inside the needle row to deflect the needles outwardly from their normal plane, a presser ring encircling the needle row and having a separate needle surface for each needle to press the beards of the deflected needles, pivoted web holders spaced apart between the presser surfaces, and bearings for the same consisting of a radially slotted portion on the outer side of the ring grooved circumferentially to receive the pivots of the web holders, substantially as described.

8. In combination in a circular knitting machine, spring beard needles, a presser device inside the needle row to deflect the needles outwardly from their normal working plane, a ring encircling the needle row and having a surface against which the beards are pressed, said ring having an outer portion slotted and grooved, web holders having pivots seated in the groove, said web holders being guided by the walls of the slots and having upwardly extending portions with fabric engaging noses thereon, the said ring being slotted to guide the nose ends of the web holders, said web holders having also outwardly extending arms, cams engaging the arms for operating them, and a slotted cage through the slots of which the arms extend and are guided, substantially as described.

9. In combination, spring beard needles, a presser device inside the needle row to deflect the needles outwardly from their normal plane, an outside presser means, a support for the inside presser device pivotally mounted to be swung out of normal position and thereby remove the inside presser, means for adjusting said support to set the presser in the desired relation to the needles, and means for locking the support in its working position, substantially as described.

10. In combination, spring beard needles, a presser device inside the needle row to deflect the needles outwardly from their normal plane, an outside presser means, a support for the inside presser device pivotally mounted to be swung out of normal position and thereby remove the inside presser, means for adjusting said support to set the presser in the desired relation to the needles, and means for locking the support in its working position, and a thread guide mounted on the presser support, substantially as described.

11. In combination, spring beard needles, a presser device inside the needle row for de-

- fecting the needles outwardly, a presser ring outside the needle row, web holders, web holder cams, and means for simultaneously adjusting the inside presser device and the web holder cams circumferentially of the needle row, substantially as described.
12. In combination, spring beard needles, a presser device inside the needle row for deflecting the needles outwardly, a presser ring outside the needle row, web holders, web holder cams, and means for simultaneously adjusting the inside presser device and the web holder cams circumferentially of the needle row, said means including a circumferentially movable member and means on the fixed frame for turning the same, substantially as described.
13. In combination, spring beard needles, a presser device inside the needle row for deflecting the needles outwardly, a presser ring outside the needle row, web holders, web holder cams, and means for simultaneously adjusting the inside presser device and the web holder cams circumferentially of the needle row, said means including a cap or cover member inclosing the web holder cams and web holders and connected with the inside presser device and said web holder cams, substantially as described.
14. In combination, spring beard needles, a presser device inside the needle row for deflecting the needles outwardly, a presser ring outside the needle row, web holders, web holder cams, and means for simultaneously adjusting the inside presser device and the web holder cams circumferentially of the needle row, said means comprising a block on the fixed frame turnable about a pivot support, a circumferentially movable member connected to said inside presser device and to the web holders cams and a pin and slot connection between the said block and said circumferentially movable member, substantially as described.
15. In combination in a circular knitting machine, spring beard needles, a presser device inside the needle row, a presser ring outside the needle row, web holders, a slotted cage in which the web holders are guided, a cap or cover member outside the cage and web holder cams held between the cage and the cover member, said cover member supporting the inside presser, substantially as described.
16. In combination in a circular knitting machine, spring beard needles, a presser device inside the needle row, an outside presser ring, pivotally mounted web holders having upper edges concentric with the pivots and having outwardly extending arms, said web holders being removable upwardly from their pivotal bearings, cams engaging said arms, a removable cover member inclosing the cams and web holders and connected with said cams, said cover member supporting the inside presser device, said removable cover holding the web holders in place through their concentric edges, substantially as described.
17. In combination in a circular knitting machine, spring beard needles, a device inside the needle row for deflecting the needles outwardly, a presser member outside the needle row, web holders, a member adjustable circumferentially and carrying the said inside presser member, a bed or cage for the web holders, web holder cams, a post for supporting the said bed and cams, and a device turnable about the post for adjusting the circumferential member to set the inside presser device in proper position, substantially as described.
18. In a circular knitting machine spring beard needles individually movable, fixed presser surfaces for the needle beards outside the needle circle, beyond the normal beard path, a needle deflector inside the needle row, means to adjust the deflector against the needle stems to force them against the beards to close them, means to lift the deflector by hand out of the needle circle to disengage the deflector from the needles to permit operating the needles up and down through the stitches without casting off the needles, and to give access to the fabric, needles, or instruments, without dismantling the parts or disturbing the working adjustment of the deflector.

In testimony whereof I affix my signature.
FRANK WILCOMB.
